UNITED STATES PATENT OFFICE.

EMIL O. LUNDIN, OF BOSTON, MASSACHUSETTS.

DESIGN FOR A JAW MEMBER FOR CARBON-CUTTING PLIERS.

SPECIFICATION forming part of Design No. 34,483, dated May 7, 1901.

Application filed March 28, 1901. Serial No. 53,361. Term of patent 14 years.

To all whom it may concern:

Be it known that I, EMIL O. LUNDIN, a citizen of the United States, residing at Boston, county of Suffolk, and State of Massachusetts, have invented and produced a new, useful, and original Design for a Jaw Member for Carbon-Cutting Pliers, of which the following is a specification, reference being had to the accompanying drawings, forming a part thereof.

The leading feature of my design for a jaw member for carbon-cutting pliers consists of two transverse recesses in the inner face of the jaw proper, between its base and point, one recess being serrated and the other beveled at one end, the outer elongated flat face of the jaw proper being roughened or file-like.

The jaw a of the jaw member has in its inner face two transverse recesses a' b, the former being serrated, as at a², and the latter having one end beveled, as at b', the outer flat face of the jaw proper being elongated and roughened or file-like, as at a³, the base of the jaw proper being extended and forming a handle a⁴.

Having fully described my design, what I claim as new, and desire to secure by Letters Patent, is—

The design for a jaw member for carbon-cutting pliers, substantially as shown and described.

In testimony whereof I have signed my name to this specification in the presence of two subscribing witnesses.

EMIL O. LUNDIN.
